WATCHMAKER'S VISE

Elmer Koski, Lake City, Minn.

Application July 8, 1949, Serial No. 103,690

4 Claims. (Cl. 81—6)

1

This invention relates to a watchmaker's vise, and more particularly to a vise for use in removing roller tables from balance wheel staffs of watches, and for similar purposes.

It is among the objects of the invention to provide an improved watchmaker's vise which is of simplified and durable construction and provides a solid support for a watch or instrument part while such part is being worked on by a watch or instrument maker; which is easily operated manually to grip and release the watch or instrument part, will hold such part without danger of damage or injury to the part, conveniently receive the part and can be quickly operated to save the time of the watch or instrument maker; which holds several work piece clamps of different sizes conveniently accessible to the watch or instrument maker; which is particularly well adapted to hold a watch balance wheel assembly for the removal of the roller table from such assembly; and which is small in size so that it does not require a large amount of space on the watchmaker's bench, is economical to manufacture, and universally usable for work on watches of different sizes and construction.

Other objects and advantages will become apparent from a consideration of the following description and the appended claims in conjunction with the accompanying drawing, wherein:

Figure 1 is a top plan view of a watchmaker's vise, illustrative of the invention;

Figure 2 is a side elevation of the vise illustrated in Figure 1;

Figure 3 is a longitudinal cross-section on the line 3—3 of Figure 1;

Figure 4 is a longitudinal cross-section on an enlarged scale of a fragmentary portion of the device and is taken substantially on the line 4—4 of Figure 1;

Figure 5 is a side elevation of a resilient chuck constituting an operative component of the device; and

Figure 6 is a side elevation of the chuck illustrated in Figure 5 with the chuck rotated 90 degrees from the position illustrated in Figure 5.

With continued reference to the drawing, the vise comprises a rectangular block, generally indicated at 10, of suitable rigid material, such as steel, iron or aluminum. This block has a length somewhat greater than its width, and a width greater than its thickness, and is provided in its normally upper face with a rectangular recess which extends transversely of the block and has a width materially less than the length of the block. This recess 11 is substantially symmetrically disposed relative to the mid-length location of the block to provide, at one end of the block, a fixed, rectangular jaw 12, and at the opposite end of the block a fixed, rectangular abutment 13 spaced from the jaw 12 by the width

2

of the recess 11. The portion of the block below the inner or bottom face of the recess 11 constitutes a flat base 14, and a movable jaw 15 is disposed in the recess 11 and slides upon the top surface of the base 14 within the recess.

The movable jaw 15 is an elongated, rectangular body, preferably of the same material of which the block 10 is formed, and has a length substantially equal to the width of the block, and a width materially less than the width of the recess 11, so that the movable jaw 15 can move toward and away from the fixed jaw 12.

The fixed jaw 12 is provided with a screw-threaded hole 16 extending therethrough substantially at the mid-length location of the jaw with its longitudinal center line substantially parallel to the bottom surface of the recess 11, and the movable jaw 15 is provided with a smooth hole 17 extending therethrough in alignment with the hole 16 in the fixed jaw 12, the hole 17 preferably being smaller than the hole 16. A screw shaft, generally indicated at 18, has an externally screw-threaded shank portion 19 threaded through the hole 16 in the fixed jaw, and has, at one end of the threaded shank portion 16, a shank extension 20 of reduced diameter which extends through the hole 17 in the movable jaw 15, and into a hole 21 in the fixed abutment 13 in axial alignment with the holes 16 and 17.

An annular shoulder 22 is provided, at the juncture of the shank extension 20, with the screw-threaded shank portion 19, and this shoulder bears against the side of the movable jaw 15 adjacent the fixed jaw 12 surrounding the hole 17 in the movable jaw. A transverse pin 23 extends through the shank extension 20 at the opposite side of the movable jaw, so that the movable jaw is clamped between the shoulder 22 and the pin 23 and is movable toward and away from the fixed jaw 12 upon longitudinal movements of the screw shaft 18 relative to the fixed jaw. An enlarged, knurled head 24 is provided on the screw shaft 18 at the end of the screw-threaded shank portion 19 opposite the shank extension 20 for manually rotating the screw shaft.

The facing ends of the fixed jaw 12 and the movable jaw 15 are provided with two sets of complementary, partly-cylindrical recesses in their adjacent edges, the two sets being disposed at respectively opposite sides of the screw shaft 18. Each set of partly-cylindrical recesses constitute a chuck-receiving socket, as indicated at 25 and 26 in Figure 1. As is particularly illustrated in Figure 4, the two recesses 27 and 28 in the fixed and movable jaw respectively, together constituting the socket 26, are disposed perpendicular to the bottom surface of the recess 11, and extend from the top surfaces of the two jaws downward partly through the thickness of the jaws, providing, at their lower ends, respective

steps or shoulders 29 and 30. A hole 31 is provided in the base 14 at the edge of the fixed jaw adjacent the recess 11 and in alignment with the partly-cylindrical recess 27 in the fixed jaw, which hole is for the purpose of receiving the shank of a resilient chuck, presently to be described.

The socket 25 is formed in the same manner as the socket 26, as described above.

Two holes or wells 32 and 33 are provided in the fixed abutment 13 extending downwardly from the top surface of this abutment, which holes are provided to receive the shanks of extra chucks, so that several chucks of relatively different sizes can be conveniently supported on the vise at the same time, and a selected chuck can be quickly inserted into one of the sockets 25 or 26 for operation of the vise.

The chucks are all of substantially identical size and construction, differing only in the formation of their work-engaging portions, so that they will conveniently hold the work pieces of different sizes, and it is, therefore, considered sufficient to describe, in detail, only one chuck, such as that generally indicated at 35.

The chuck 35 comprises a cylindrical portion 36, and a cylindrical stem or shank 37 projecting outwardly from one end of the cylindrical portion 36 substantially concentric with the latter. The cylindrical portion 36 is symmetrically divided by a transversely-extending notch 38 which extends from the end of the shank 37 adjacent the cylindrical portion 36 to the opposite end of the cylindrical portion and uniformly increases in width in a direction away from the shank 37. A pair of opposed jaws 39 and 40 extends outwardly from the end of the cylindrical portion 36 opposite the shank 37, and are disposed at respectively opposite sides of the slot 38.

The jaws have a width less than the diameter of the cylindrical portion 36, are symmetrically disposed relative to the center of the symmetrical portion and have their outer sides beveled, or inclined so that they terminate in narrow outer ends. Each of these jaws has, at its outer end, a lip, as indicated at 41 and 42 respectively, directed toward the opposite jaw to engage a work piece, such as a watch balance wheel assembly.

Adjacent the lips 41 and 42 the slot 38 is enlarged to provide a substantially cylindrical recess 48 extending transversely between the jaws immediately under the lips and the mutually adjacent edges of the lips are semi-circularly recessed to provide two complementary halves 49 and 50 of a substantially circular opening between the jaws. A notch is provided in the end of each jaw, as indicated at 51 and 52, which notches provide clearance for the roller jewel when the roller table is seated on the jaws so that the jewel will not be damaged in the process of removing the balance wheel staff from the roller table.

The cylindrical portion 36 of the chuck is of substantially the same diameter as the sockets 25 and 26 provided by the complementary, partly-cylindrical recesses, such as 27 and 28, provided in the fixed and movable jaws 12 and 15, respectively.

In using the device, a chuck is placed in one of the sockets 25 or 26 with the notch 38 in the chuck substantially in alignment with the gap between the fixed and movable jaws of the device, and with the chuck jaws 39 and 40 positioned above the fixed and movable jaws 12 and 15. A watch balance wheel assembly, generally indi-

cated at 43 in Figure 4, is then placed on the chuck jaws in a manner such that the chuck jaws project through spaces between the arms or spokes and the rim of the balance wheel 44, the roller table 45 of the balance wheel assembly rests upon the top surfaces of the chuck jaws, and the roller jewel overlies the notches in the ends of the jaws. The screw shaft 18 is then manually rotated to move the movable vice jaw 15 toward the fixed vice jaw 12 compressing the chuck 35 and forcing the chuck jaws 39 and 40 toward each other to firmly grip the hub 46 of the balance staff 47 with the balance wheel staff 47 projecting downwardly between the chuck jaws, the balance wheel assembly being firmly held on the chuck jaws by the left hand of the watchmaker while the watchmaker rotates the screw shaft with his right hand by means of the knurled head 24 on the screw shaft.

After the balance wheel assembly 43 has been clamped in the chuck jaws, a punch of the proper size is set on the upper end of the balance wheel staff 47 and positioned substantially vertically and in axial alignment with the balance wheel staff. The upper end of the punch is then given a sharp blow with a small hammer to drive the staff out of the roller table 45. After the staff has been removed from the roller table, the screw shaft 18 is rotated in a direction to move the movable vice jaw 15 away from the fixed vice jaw 12 permitting the chuck 35 to expand, whereupon the disassembled balance wheel assembly can be easily removed from the chuck.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

- 45 1. A watchmaker's vise comprising a base, an abutment and a fixed jaw projecting laterally from a side of said base and spaced along said base from each other, a movable jaw located at said side of the base and positioned between said abutment and said fixed jaw, said fixed jaw having a threaded bore extending therethrough longitudinally of said base and spaced from said side of the base, said abutment having a smooth bore extending therethrough in axial alignment with said threaded bore, and said movable jaw having a smooth bore extending therethrough and axially aligned with the bore of the abutment and threaded bore of the fixed jaw, the bores of the abutment and movable jaw being smaller in diameter than the threaded bore of the fixed jaw, a screw threaded in and extending through said threaded bore, said screw having a longitudinally inward end positioned in the space between the fixed jaw and said abutment, a reduced axial extension on the longitudinally inward end of the screw, the juncture of the screw and said extension defining a shoulder, said extension being smooth and extending slidably and rotatably through the smooth bores of the movable jaw and abutment, with said shoulder engaging an end of the movable jaw, and means engaging said extension and the other end of the movable jaw and holding said movable jaw against said shoulder.
- 50 2. A watchmaker's vise comprising a base, an
- 55
- 60
- 65
- 70

abutment and a fixed jaw projecting laterally from a side of said base and spaced along said base from each other, a movable jaw located at said side of the base and positioned between said abutment and said fixed jaw, said fixed jaw having a threaded bore extending therethrough longitudinally of said base and spaced from said side of the base, said abutment having a smooth bore extending therethrough in axial alignment with said threaded bore, and said movable jaw having a smooth bore extending therethrough and axially aligned with the bore of the abutment and threaded bore of the fixed jaw, the bores of the abutment and movable jaw being smaller in diameter than the threaded bore of the fixed jaw, a screw threaded in and extending through said threaded bore, said screw having a longitudinally inward end positioned in the space between the fixed jaw and said abutment, a reduced axial extension on the longitudinally inward end of the screw, the juncture of the screw and said extension defining a shoulder, said extension being smooth and extending slidably and rotatably through the smooth bores of the movable jaw and abutment, with said shoulder engaging an end of the movable jaw, and means engaging said extension and the other end of the movable jaw and holding said movable jaw against said shoulder the facing ends of the fixed and movable jaws having complementary semi-circular recesses extending laterally inwardly therein, said recesses being in spaced relation to the said side of the base.

3. A watchmaker's vise comprising a base, an abutment and a fixed jaw projecting laterally from a side of said base and spaced along said base from each other, a movable jaw located at said side of the base and positioned between said abutment and said fixed jaw, said fixed jaw having a threaded bore extending therethrough longitudinally of said base and spaced from said side of the base, said abutment having a smooth bore extending therethrough in axial alignment with said threaded bore, and said movable jaw having a smooth bore extending therethrough and axially aligned with the bore of the abutment and threaded bore of the fixed jaw, the bores of the abutment and movable jaw being smaller in diameter than the threaded bore of the fixed jaw, a screw threaded in and extending through said threaded bore, said screw having a longitudinally inward end positioned in the space between the fixed jaw and said abutment, a reduced axial extension on the longitudinally inward end of the screw, the juncture of the screw and said extension defining a shoulder, said extension being smooth and extending slidably and rotatably through the smooth bores of the movable jaw and abutment, with said shoulder engaging an end of the movable jaw, and means engaging said extension and the other end of the movable jaw and holding said movable jaw against said shoulder, the facing ends of the fixed and movable jaws having complementary semi-circular recesses extending laterally inwardly therein, said recesses being in spaced relation to the said side of the base, said fixed and movable jaws having reduced diameter extensions of said semi-circular recesses axially aligned with said semi-circular recesses and opening thereinto at the laterally inward ends of the semi-circular recesses, the juncture of the recesses and the extensions thereof defining shoulders at the laterally inward ends of the recesses, said base being provided with a bore axially aligned with and opening at one end into the

laterally inward ends of said recess extensions.

4. A watchmaker's vise comprising a base, an abutment and a fixed jaw projecting laterally from a side of said base and spaced along said base from each other, a movable jaw located at said side of the base and positioned between said abutment and said fixed jaw, said fixed jaw having a threaded bore extending therethrough longitudinally of said base and spaced from said side of the base, said abutment having a smooth bore extending therethrough in axial alignment with said threaded bore, and said movable jaw having a smooth bore extending therethrough and axially aligned with the bore of the abutment and threaded bore of the fixed jaw, the bores of the abutment and movable jaw being smaller in diameter than the threaded bore of the fixed jaw, a screw threaded in and extending through said threaded bore, said screw having a longitudinally inward end positioned in the space between the fixed jaw and said abutment, a reduced axial extension on the longitudinally inward end of the screw, the juncture of the screw and said extension defining a shoulder, said extension being smooth and extending slidably and rotatably through the smooth bores of the movable jaw and abutment, with said shoulder engaging an end of the movable jaw, and means engaging said extension and the other end of the movable jaw and holding said movable jaw against said shoulder, the facing ends of the fixed and movable jaws having complementary semi-circular recesses extending laterally inwardly therein, said recesses being in spaced relation to the said side of the base, said fixed and movable jaws having reduced diameter extensions of said semi-circular recesses axially aligned with said semi-circular recesses and opening thereinto at the laterally inward ends of the semi-circular recesses, the juncture of the recesses and the extensions thereof defining shoulders at the laterally inward ends of the recesses, said base being provided with a bore axially aligned with and opening at one end into the laterally inward ends of said recess extensions, a chuck having a compressible cylindrical portion removably and conformingly engaging said semi-circular recesses and a reduced shank on one end engaging in said recess extensions and the bore in the base with the said one end of said cylindrical portion engaging said shoulders, said cylindrical portion being slotted from its other end to define a pair of work-engaging jaws arranged to be compressed toward each other to clamp work therebetween by movement of said movable jaw toward said fixed jaw by operation of said screw.
